UNITED STATES PATENT OFFICE.

ALBERT J. GRANBERG, OF SAN FRANCISCO, CALIFORNIA.

PIPE-WRENCH.

1,306,534.

Specification of Letters Patent. Patented June 10, 1919.

Application filed February 11, 1918. Serial No. 216,429.

To all whom it may concern:

Be it known that I, ALBERT J. GRANBERG, a citizen of the United States, residing at San Francisco, in the county of San Francisco and State of California, have invented 5 new and useful Improvements in Pipe-Wrenches, of which the following is a specification.

The present invention relates to improvements in pipe wrenches, the purpose of the invention being to provide a pipe wrench which can be used to turn a pipe lying close to a wall or other object and which will be strong and durable, which can be readily 10 adjusted for different sizes of pipes, which will automatically, when applied to the pipe, grip the same initially, so that immediately upon the movement of the hand to turn the pipe the grip upon the pipe will 15 be strengthened, and by which on a further movement of the hand, the pipe can be gripped with a very powerful pressure, thus absolutely preventing slippage of the wrench upon the pipe.

In the accompanying drawing Figure 1 20 is a side view of my improved pipe wrench; Fig. 2 is a longitudinal section of the same; Fig. 3 is a transverse section on the line 3—3 of Fig. 1.

Referring to the drawing, 1 indicates a 25 stationary jaw and 2 a movable or adjustable jaw. Said jaws 1, 2, are provided with opposing serrated surfaces, 3, 4, respectively, which, when the jaws are in their proper 30 relative positions diverge slightly from each other. The jaw 2 is provided with a guide 6 extending in a direction in general transverse to the working face 4 of the jaw, and projecting considerably in front of said 35 working face. Said guide is of an approximately cylindrical form, and is connected to the jaw by a narrow neck 7. Said guide moves in a guideway 8 extending in the jaw 1 in a direction transverse to the working 40 face 3, the sides of said guideway approaching each other at the top on opposite sides of the narrow neck 7 to prevent the guide being withdrawn from the guideway in a transverse direction. In order that said 45 guide may be moved longitudinally in the guideway to vary the distance between the working faces of the jaws, the guide is formed on the side opposite to the jaw 2 with a rack 9. This rack can engage the 50 threads of a worm 11, rotatable and slid-

able on a shaft 12, extending into said jaw 1 parallel with the guide, the inner end of said shaft being screwed into said jaw 1. The jaw 1 has an opening 10 therethrough extending from side to side, in which opening the worm 11 is located, and which permits the finger and thumb of the operator to contact with opposite sides of said worm, for the purpose of rotating the same, for which purpose also the edges of the worm 55 are milled, as shown at 13.

The handle 14 of the wrench is pivoted to the jaw 1 by a pivot pin 16 extending transversely through said jaw, and of which the inner end is screwed into the jaw, the lower 70 portion of said jaw being bifurcated to receive the upper reduced portion of said handle. Said reduced portion has at its upper end a forked extension 17, the members of which extend on opposite sides of shaft 12, 75 and can bear against an end of the worm 11 on said shaft. It will be observed that the position of the pivot 16 is such that the motion of the extension 17 is substantially in alignment with the motion of the worm 11 80 so that there is very little lateral motion of said extension 17 upon the end of the worm.

A light spring 18, riveted at one end, as shown at 19, to the jaw 1, bears at its other end against a shoulder 22 of said handle, 85 and turns said handle about the shaft 16 and thereby presses said forked extension against said worm. A side of the transverse opening 10 forms a stop to limit the longitudinal movement of said worm with the 90 inward movement of said guide 6, and a shoulder 23 on the jaw 1, adjacent to the spring 18, by limiting the corresponding movement of the handle 14, limits the longitudinal movement of the worm opposite 95 to that first named, to prevent the extension 17 from moving out of engagement with the end of the worm due to its pivotal or lateral movement while the worm moves longitudinally outward. This effect would also be 100 attained by the extension 17 striking against the portion of the jaw 1 in which is the head of the screw 12.

The following is the mode of use of the wrench: The worm is first turned to move 105 the movable jaw to such a distance from the first jaw that the outer ends of the jaws are spaced apart slightly less than the diameter of the pipe to be turned by the wrench. The jaws are then applied on opposite sides 110

of the pipe, and the wrench is moved toward the pipe, causing the movable jaw to slide outwardly, carrying with it the worm, against the slight pressure of the spring 18, 5 which pressure is, however, sufficient to cause the jaws to grip the pipe. Then, if the handle be turned in the direction away from the spring, the effect will be to cause the extension 17 of the handle to bear against 10 the worm and press it toward the stationary jaw, thereby causing also the movable jaw to move toward the stationary jaw, and firmly gripping the pipe wrench so that, in the continued movement of the handle, the 15 pipe gripped thereby is turned.

It will therefore be seen that my improved pipe wrench possesses all the desirable qualities of a pipe wrench, namely, that it is of great strength, that it can be easily adjusted 20 to different sizes of pipes, that it immediately, when applied to the pipe, furnishes an initial grip on the same, and that, when the turning movement is commenced, the grip is correspondingly increased.

25 But perhaps the most striking advantage of my improved wrench is that it can be used to turn pipes which are close to a wall or other object and which cannot be gripped by the ordinary pipe wrench.

30 I claim:

1. A wrench comprising a fixed jaw, a 35 slideable jaw arranged on said fixed jaw, a worm arranged in said fixed jaw and engaged with said slideable jaw for controlling the movement thereof relative to said fixed jaw, and a handle pivoted in said fixed jaw and having an extension for engaging one end of said worm, the pivot of the handle

being so located that said extension will overlap the end of the worm in all positions 40 of the handle, said worm being mounted to slide freely longitudinally toward said extension when said handle is turned in a direction to permit the jaws to separate, whereby movement of the handle in the opposite direction causes said extension to engage and move the worm, thus effecting movement of the slideable jaw toward the fixed jaw for gripping the work.

2. A wrench comprising a fixed jaw, a 50 slideable jaw arranged on said fixed jaw, a worm arranged in said fixed jaw and engaged with said slideable jaw for controlling the movement thereof relative to said fixed jaw and supported upon a fixed pivot pin 55 for free limited longitudinal movement in said fixed jaw when permitted by the handle, and a handle pivoted in said fixed jaw adjacent one end of said worm and having an extension underlying said end of the worm, the handle pivot being so located that said extension will move in a curved path lying substantially in the direction of the axis of said worm and will remain in position to engage the end of the worm in all positions of 60 said handle, movement of the handle on the working stroke of said wrench serving to move said extension against said worm in the same direction as and coextensively with the longitudinal movement of said worm, and movement of the handle in the opposite direction permitting the worm to have unrestrained movement within the limits of 65 travel of said extension.

A. J. GRANBERG.
